LLP/S.E.N.C.R.L., s.r.l.(57) **CLAIM**

The ornamental design for a curtain rod finial, as shown and described.

DESCRIPTION

FIG. 1 is a side perspective view of a curtain rod finial; FIG. 2 is a first end view of the curtain rod finial of FIG. 1; FIG. 3 is a side view of the curtain rod finial of FIG. 1; and, FIG. 4 is a second end view of the curtain rod finial of FIG. 1.

The broken lines in the drawings illustrate portions of a curtain rod finial which form no part of the claimed design.
